UNITED STATES PATENT OFFICE.

ELIHU THOMSON, OF NEW BRITAIN, CONNECTICUT, ASSIGNOR TO THE AMERICAN ELECTRIC COMPANY, OF SAME PLACE.

ELECTRO-MAGNETIC DEVICE.

SPECIFICATION forming part of Letters Patent No. 250,175, dated November 29, 1881.

Application filed February 9, 1881. (No model.)

To all whom it may concern:

Be it known that I, ELIHU THOMSON, a citizen of the United States, residing at New Britain, county of Hartford, State of Connecticut, 5 have invented a new and useful Electro-Magnetic Device, of which the following is a specification.

The object of my invention is to obtain a greatly-increased attractive energy in electro-magnetic coils with movable cores, and also to construct a coil which when traversed by an electric current shall exert an axial attraction upon a movable core partially inclosed thereby, which attraction shall be practically constant for a constant current, independently of changes of position within certain limits.

I apply my invention to all cases where great attractive energy is to be exerted through a considerable range of position of the moving core, and where the tendency of a core to enter a coil is required to be the same in various positions when a constant current circulates.

My invention is adapted to operate regulators for electric currents, electric-lamp mechanism, signal apparatus, &c.

Briefly, my invention consists of a coil of insulated conductor, through which an electric current can be sent, surrounded by an iron casing and inclosing a movable core, having 30 certain relations to a conical extension of iron, as herein described.

Figure 1 is a side view of the device, where C is a helix or coil of wire; I, a lateral outer casing of iron; P, an iron base-plate, and conical extension P'; H, a movable iron tube or hollow core. Fig. 2 is in all respects similar to Fig. 1, except that the parts are inverted.

Referring to Fig. 1, C is a coil through which a current of electricity is passed, which causes 40 an axial attraction of the core, H, of iron, into the interior of said coil; but this attractive force is very feeble when coil and core only are used.

My improvement consists in adding an external iron casing extending from the top of the coil C over its sides and to the iron base-plate P. I am thus enabled to obtain from a given core from four to five times the mechanical energy in entering the coil C as would be 50 obtained without the casing; but to further

improve my device and enable it to be readily adapted to its various uses, I procure an attractive energy constant for the same current strength, notwithstanding changes of position of the core H with respect to the coil C, by the 55 introduction of an iron extension, P', extending upward in the center of the coil from the base-plate P. A central rod is attached to the core H, by means of which its force may be transmitted. A weight, W, is sometimes used 60 to counterbalance, either partly or entirely, the weight of the core H. A brass tube, J, surrounds the movable core H, and it is preferably filled with oil or glycerine, in order to 65 damp or check sudden motions of the core. The casing need not cover the coil C completely, but may consist of any mass of magnetic substance serving to join and convey the magnetic polarization around the exterior of the coil C, and from end to end exteriorly. 70

Fig. 2 shows the parts inverted, and this is sometimes a convenient disposition.

The object of the cone P' is to compensate for the diminished axial force of the coil C upon the core H as it enters the coil. It is 75 well known that when a plain iron core is attracted into a helix the magnetic effect rises to a maximum, then falls to a minimum or zero, when the center of the coil is in the same position as the center of the core, and various 80 devices have been attempted to overcome this changing force and render it more uniform. The coil itself has been wound tapering, the core has had various outlines given to it, counterbalancing devices used to increase and diminish their effect upon the core, and thus obtain uniformity of action in various positions; but I do not find that by any other device than my present invention, or its manifest equivalent, powerful attractive energy and uniform 85 attraction in various positions have been realized, and I attribute my results to the casing or closed magnetic circuit outside the coil operating in conjunction with the annular core H and conical extension P'. The motion of the 90 core H toward the base of the cone P' brings the sides of the cone or taper P' nearer the core H, and there results an increased attractive force, which is greater as the direct axial force of the coil C upon the core H is less, and 95

by properly shaping the parts, the variations of the one being opposite to those of the other, a uniform tendency of the core H to move within its coil C axially is produced with the same current.

With various dimensions of parts experiment will determine the proper proportions to be employed to obtain all the effects desired; but for the guidance of those skilled in the art 5 to a single example will be given. I have made the coil five inches in length, five inches external diameter, three inches internal diameter; the core H five inches long, two and three-fourths external diameter, and two and one-fourth internal diameter; the cone P' two 10 and three-fourths inches high, two inches wide at base, and tapering upward nearly to a point. With a casing about one-fourth inch thick an attractive force is obtained practically uniform 15 for a range of one and one-fourth inch movement of the core when a constant current is flowing through the coil. An equivalent arrangement is to provide the core H with a tapering conical extension and cut a circular opening in the base-plate P, through which the taper extremity of the core may pass as 20 said core is drawn into the coil C. It is thus 25 that the iron of the core gradually gains prox-

imity to the base-plate and uniformity of action is obtained.

30

I claim as my invention—

1. In combination with a hollow movable core placed in the interior of a coil of wire or helix, an external casing and tapering extension connected to said casing for the purpose 35 of obtaining an axial attractive force constant for a constant current, independently of changes of position of said core with respect to said coil within practicable limits.

2. A movable core, H, surrounded by a coil 40 of insulated wire and immersed in a vessel of oil or glycerine, and whereby said core is checked in its movement, in consequence of the resistance to the passage of said oil or glycerine from a position above said core to a position 45 below it, and vice versa.

3. The combination, in an improved electro-magnetic device, of the following elements, viz: a coil or helix, a movable core, a vessel 50 of oil or glycerine in which said core moves, an exterior iron casing, and tapering extension of the same interior to said coil or helix.

ELIHU THOMSON.
